UNITED STATES PATENT OFFICE

WILLIAM E. WINE, OF TOLEDO, OHIO

INTERCHANGEABLE VOLUTE SPRING UNIT

Application filed June 4, 1928. Serial No. 282,800.

The invention relates to springs for use in railway car trucks for supporting the truck bolster.

It is well known that it is the usual practice to provide a nest of helical springs mounted within the window opening of a truck side frame for supporting the load, the springs varying in number according to the capacity of the car for which they are provided and being generally symmetrically grouped and confined between plates or caps. In the standard A.R.A. truck construction there is a definite space within which the springs are located. As cars of greater capacity are built in accordance with the developments in the railroad art it becomes necessary to increase the capacity of the springs which support the load. Originally, when the car capacity was low, the number of springs used and the capacity of the individual springs was small. As heavier cars have been built it has been found necessary to increase the number of springs in the cluster or nest and it is now a common practice to provide groups of five springs. Owing to the limitations in the design of spring assemblies resulting from the necessity for conforming to standard dimensions, and requirements as to travel, it becomes a difficult proposition to increase the capacity of the spring assembly beyond a certain limit. To use a greater number of springs in a group or cluster involves the employment of a specially constructed side frame with a larger window opening than ordinarily. This solution of the difficulty is objectionable as it entails the making of new equipment and precludes the use of already existing side frames. For these reasons efforts have been made to increase the capacity of the well known helical springs by constructing them of special alloys and resorting to other efforts known to spring makers, for instance different methods of heat treatment, etc. It has also been contemplated that use be made of a spring assembly including combinations of helical and circular plate springs, and circular plate or disk springs alone to increase the capacity. However, regardless of

which expedient has been resorted to, all are open to the same objection, namely: that the springs are not resilient under light or intermediate loads and this is particularly true in cases where there has been an increase in the number of springs in the cluster. 55

It is known to engineers and others that a spring of the volute type possesses great capacity for the amount of material from which it is formed. This fact has been taken advantage of in the design of spring and combined spring and friction draft gears as evidenced by their employment particularly in foreign countries. In the early days of railroad development certain attempts were made to employ volute springs in connection with railway car trucks but as the conditions as to travel and capacity existing at that time are not comparable to those in modern practice these first attempts are of little significance especially as there was no necessity for overcoming difficulties such as exist today. 60 65 70

It should also be mentioned that helical springs all have a definite period of vibration which synchronize with one another and which if synchronized with the passage of the car wheels over rail joints will result in the development of car roll or side sway 75 80 which if permitted to continue may cause derailment. It is known that a volute spring, owing to the plurality of convolutions of different diameters does not possess a definite period of vibration, a fact of 85 which I take advantage in the carrying out of my invention.

It is with all of the above facts in view that I have devised the present invention which has for its general object the substitution of volute springs for helical springs for resiliently supporting the bolsters in car trucks. 90

An important object of the invention is to provide an assembly of volute springs preferably symmetrically arranged in accordance with the established grouping of helical springs and of such size as to be used in connection with the end plates or caps of a standard spring nest so that the assembly 95 100

will be capable of replacing a standard A.R.A. helical spring nest, it being consequently possible to provide a greatly increased spring capacity in existing trucks 5 without any change whatsoever in the construction of the trucks themselves.

Another object of the invention is to provide a spring assembly comprising the combination with standard A.R.A. spring caps 10 of a group or cluster of volute springs arranged in a manner corresponding to the customary helical spring arrangement, together with filler means which will compensate for the difference between the 15 length of standard helical springs and the length or height of volute springs of a given desired capacity, the entire assembly being consequently usable as a replacement.

Another feature of the invention is the 20 elimination of possibility of synchronization of spring vibration by employing a system of volute springs, together with the obtaining of resilience under light and intermediate load conditions.

25 To the attainment of the foregoing and other objects and advantages, the invention preferably consists in the details of construction and the arrangement and combination of parts to be hereinafter more fully 30 described and claimed, and illustrated in the accompanying drawing in which:

Figure 1 is a view partly in top plan and partly in horizontal section showing a spring assembly constructed in accordance with my 35 invention,

Figure 2 is a cross sectional view taken on the line 2—2 of Figure 1,

Figure 3 is a detail side elevation of one 40 of the filler members alone,

Figure 4 is a side elevation of one of the spring retaining or centering devices.

Figure 5 is a side elevation showing a modification of the spring cap,

Figure 6 is a detail plan view of a modified 45 form of filament.

Referring more particularly to the drawing, the numeral 1 designates the top and bottom spring caps which preferably conform to the standard A.R.A. design and 50 which are preferably similar or identical in construction. The type of cap illustrated is of plate-like form and of the customary shape for use with a cluster of five springs. The cap is provided with a plurality of 55 circular depressed portions defining projections 2 provided for the purpose of extending into the ends of the usual helical springs for centering them properly and for restraining them against any lateral displacement during deflection. As the plates 60 are formed of sheet metal and as the projections 2 are defined by stamping, each projection is formed with a central opening 3. In the ordinary type of spring assembly in 65 which helical springs are used in conjunc-

tion with these caps it is the practice to hold the parts assembled by means of a bolt 4 passing through the openings in the central projections in exactly the same manner illustrated in Figure 2 in the present instance. 70 Obviously more of such bolts could be provided extending through others of said projections if such be found advisable or advantageous for any reason.

In carrying out the present invention the 75 usual helical springs are replaced by volute springs 5. In the present instance I have shown the helical springs as entirely eliminated and replaced by a corresponding number of volute springs though it is conceivable 80 that a combination of the two types might be provided if desired. The thickness or gauge, the width and also the length of the stock from which each volute spring is formed necessarily depends upon the contemplated 85 capacity in relation to the travel and these factors will also determine the number of convolutions. The spacing of the convolutions naturally depends upon whether or 90 not there is any intention that they come in contact and produce friction at a certain point in their travel or during deflection. If no friction is desired it is obvious that the spacing must be sufficient that there will be no contact between the convolutions at any 95 time during closure of the spring.

The volute springs are of course located upon the bottom cap and if the cap be of the described type as shown in Figures 1 and 2 I contemplate providing cups 6 within 100 which the lower ends of the springs fit, the cups themselves being centrally apertured at 7 for the accommodation of the projections 2. These cups will function as means for properly centering the springs and for preventing them from lateral displacement. If use be made of the type of cap shown at 105 8 in Figure 5, in which type there are flanges 9 at the corners, such cups might be omitted. It is preferable that the volute springs have the same travel as the usual helical 110 springs which they replace but as it is clear that there is no abutting engagement of the convolutions in a volute spring as compared with the engagement of the coils in a helical spring a volute spring of a given travel and capacity will be of considerably less 115 height than a helical spring. It is for this reason that I provide filler means in association with the volute springs to compensate for the difference mentioned. Accordingly 120 I make use of filler members 10 corresponding in number to the number of volute springs and interposed between the upper ends thereof and the underside of the top cap. Each filler member is recessed at its upper side as shown at 11 for the accommodation of the projection 2 and is provided 125 at its underside with a projection 12 corresponding to the projection 2 and adapted 130

to fit within the smallest convolution of the volute spring to center the same and retain it against lateral displacement. The entire assembly is held assembled by one or more 5 bolts 4 as above described and it is apparent that it may be inserted within the window opening in a truck in the usual manner. The spring caps of this and other similar types are generally provided with projections 10 13 which fit within corresponding recesses, not shown, in the underside of the truck bolster and in the spring plank.

When the spring assembly is in use it is clear that owing to the very nature or the 15 inherent characteristics of volute springs there will be a resilient supporting action even under lightest load conditions. By specially forming the volute springs from stock of varying width or varying thickness, for 20 instance as disclosed in the co-pending application of Cyrus J. Holland, Serial No. 208,349, filed July 25th, 1927, it is easily possible to vary the relation of the travel to load variations. If desired, the volute 25 springs may be formed as indicated in my co-pending application filed May 1st, 1928, Serial No. 274,307, wherein I have disclosed a construction in which the corner of the stock from which the spring is formed is laterally offset to define a flat bearing portion. Said co-pending application shows this construction at the innermost and outermost convolutions but if such a spring be used in the present instance it is preferable 30 that only the inner convolution have this flattened portion. If use be made of such springs then it would be necessary to modify the filler members 10 and they would then be formed as shown in Figure 6 wherein the 35 filler 10^a is represented as having an extension 12^a which is not cylindrical but which is so shaped as to be received within the innermost convolution with due allowance for the flattened surface thereon.

40 A distinct feature of advantage incident to the employment of volute springs in this connection is that they have no definite period of vibration and there will consequently be a total absence of synchronization which 45 so frequently results in the development of excessive car roll or side sway. From the foregoing it is believed that the construction, operation and advantages will be readily apparent to one skilled in the art without further explanation.

While I have shown and described the preferred embodiments of the invention, it should be understood that the disclosure is 50 merely an exemplification of the principles involved as the right is reserved to make all such changes in the details of construction as will widen the field of utility and increase the adaptability of the device provided such changes constitute no departure

from the spirit of the invention or the scope of the claims hereunto appended.

Having thus described the invention, I claim:

1. A truck spring assembly comprising the combination of standard spring caps, volute springs arranged therebetween, and means cooperating with the springs and one of the caps to compensate for the difference between the height of standard helical springs and corresponding volute springs having the same or a greater capacity with the same travel. 70

2. The combination with a standard truck side frame and bolster, of a spring assembly 80 serving as a replacement for an A.R.A. standard spring nest and comprising top and bottom caps, a plurality of volute springs arranged therebetween, and filler means interposed between one cap and the adjacent ends of the volute springs to compensate for the difference between the height of standard helical springs and the height of volute springs having the same travel but a different capacity. 85

3. A spring assembly for supporting a truck bolster within a truck side frame, comprising the combination with A.R.A. standard spring caps, of volute springs arranged between the caps, the caps having projections extending toward each other, and filler members engaged between one cap and the adjacent ends of the volute springs, the filler members being recessed for the accommodation of the projections on one cap and being formed with corresponding projections entering the springs. 95

4. A spring assembly for supporting a truck bolster within a truck side frame, comprising the combination with A.R.A. standard spring caps, of volute springs arranged between the caps, the caps having projections extending toward each other, filler members engaged between one cap and the adjacent ends of the volute springs, the filler members being recessed for the accommodation of the projections on one cap and being formed with corresponding projections entering the springs, and means on the other cap for centering the volute springs and restraining them against lateral displacement. 100

5. A spring assembly for supporting a truck bolster within a truck side frame, comprising the combination with A.R.A. standard spring caps, of volute springs arranged between the caps, the caps having projections extending toward each other, filler members engaged between one cap and the adjacent ends of the volute springs, the filler members being recessed for the accommodation of the projections on one cap and being formed with corresponding projections entering the springs, and means engaged upon the pro- 110 120 125 130

jections on the other cap engaging the adjacent ends of the volute springs.

6. A spring assembly for supporting a truck bolster within a truck side frame, comprising the combination with A.R.A. standard spring caps, of volute springs arranged between the caps, the caps having projections extending toward each other, filler members engaged between one cap and the adjacent end of the volute springs, the filler members being recessed for the accommodation of the projections on one cap and being formed with corresponding projections entering the springs, and means engaged upon the projections on the other cap engaging the adjacent ends of the volute springs in encircling relation thereto.

7. A spring assembly for supporting a truck bolster within a truck side frame, comprising the combination with A.R.A. standard spring caps, of volute springs arranged between the caps, the caps having projections extending toward each other, filler members engaged between one cap and the adjacent ends of the volute springs, the filler members being recessed for the accommodation of the projections on one cap and being formed with corresponding projections entering the springs, and cup members centrally apertured for engagement upon the projections on the other cap and encirclingly engaging the other ends of the volute springs.

8. A spring assembly for supporting a truck bolster within a truck side frame, comprising the combination of spring caps, volute springs arranged therebetween, the caps having projections extending toward each other, and filler members engaged between one cap and the adjacent ends of the volute springs, the filler members being recessed for engagement with said projections on one cap and having extensions entering the springs.

45 9. A spring assembly for supporting a truck bolster within a truck side frame, comprising the combination of spring caps, a plurality of volute springs arranged therebetween, filler members arranged between one cap and the adjacent ends of the volute springs, means preventing lateral displacement of the filler members with respect to the cap engaged by them, and means on the filler members engaging and centering said springs.

60 10. A spring assembly for supporting a truck bolster within a truck side frame, comprising the combination with spring caps, of volute springs arranged therebetween, and means for centering and retaining the springs comprising individual filler members corresponding in number to the number of springs disposed against one cap and having projections entering the innermost convolutions of the springs and shaped

to conform to the opening within the innermost convolution.

65 11. A truck spring assembly comprising spring caps, a plurality of volute springs arranged therebetween, filler members disposed against one cap and having projections entering and having an external shape corresponding to that of the inner peripheries of the inner convolutions of the springs, means engaging within said filler members for holding them against displacement, and means carried by the other cap and engaging the outermost convolutions of said springs for assisting in centering them.

12. A spring assembly for supporting a truck bolster comprising spring caps having projections extending toward each other, a plurality of volute springs arranged between the caps, filler members disposed against one cap and receiving the projections thereon and having projections engaged within the volute springs, and cup members disposed against the other spring cap and embracing the large ends of the volute springs, said cup members being apertured and receiving the projections on the second named cap.

13. A railway car truck spring assembly involving spaced spring caps of the type having portions projecting toward each other for centering a helical spring adapted to be disposed therebetween, a volute spring disposed between the spring caps, and members respectively interposed between the spring caps and the adjacent ends of the volute spring and constituting means for centering the latter, each of said interposed members having a portion receiving a projecting portion of the adjacent spring cap and being thereby restrained from lateral displacement relatively to the spring.

14. A railway car truck spring assembly involving spaced spring caps of the type having portions projecting toward each other for centering a helical spring adapted to be disposed therebetween, a volute spring disposed between said spring caps, and a filler member interposed between one end of the volute spring and the adjacent spring cap, said interposed member having a portion receiving the projecting portion of the said adjacent spring cap and being thereby restrained from lateral displacement with respect to said cap.

15. A railway car truck spring assembly involving spaced spring caps of the type having portions projecting toward each other for centering a helical spring adapted to be disposed therebetween, a volute spring disposed between said spring caps, and means for centering the volute spring involving a member interposed between one end of the spring and the adjacent spring cap, said interposed member being recessed to receive the said projecting portion of the

said last named spring cap and being restrained by said portion from lateral displacement with respect to the spring cap.

16. A railway car truck spring assembly 5 involving spaced spring caps of the type having inwardly projecting bosses for centering a helical spring adapted to be interposed therebetween, a volute spring disposed between said spring caps, and means for 10 centering the volute spring involving a member interposed between one end of the latter and the adjacent spring cap, said interposed member having a portion encircling the boss of the last named spring cap and 15 being restrained by said boss from lateral displacement with respect to the said spring cap.

17. A railway car truck spring assembly 20 involving spaced spring caps of the type which are adapted to receive a helical spring therebetween and which are respectively formed with body portions against which the spring is adapted to seat and also formed with inwardly extending projections adapt- 25 ed to center the spring, a volute spring disposed between said spring caps, and a filler member engaging the body portion of one of said spring caps and interposed between the latter and the adjacent end of the volute 30 spring, said filler member being recessed to receive the inwardly extending projections of the adjacent spring cap whereby lateral movement of the filler member with respect to the spring cap is prevented.

35 18. A railway car truck spring assembly involving spaced spring caps of the type which are adapted to receive a helical spring and which are respectively formed with inwardly extending projections adapted to 40 center the helical spring, a volute spring disposed between said spring caps, and means for centering the volute spring involving a member interposed between one end of the latter and the adjacent spring 45 cap, said member having portions arranged in overlapping relation to the outermost convolution of the spring and formed to receive the projection of the adjacent spring cap for preventing relative lateral displacement 50 between said cap and member.

19. A railway car truck spring assembly 55 involving spaced spring caps of the type which are adapted to receive a helical spring and which are respectively formed with inwardly extending projections adapted to 60 center the helical spring, a volute spring disposed between said spring caps, and means for centering the volute spring involving a member interposed between one end of the latter and the adjacent spring cap, said member having an annular flange aranged in overlapping relation to the outermost convolution of the volute spring and 65 having an aperture located centrally of the flange for receiving the projection of the

spring cap to prevent relative lateral displacement of said member and cap.

20. A railway car truck spring assembly 70 involving spaced spring caps of the type which are adapted to receive a helical spring and which are respectively formed with inwardly extending projections adapted to center the helical spring, a volute spring disposed between said spring caps, and means for centering the volute spring involving 75 a member interposed between one end of the latter and the adjacent spring cap, said member being apartured to receive the said projection of the said adjacent spring cap and preventing lateral displacement of the 80 member relatively to the cap and being provided with an annular marginal flange over- 85 lappingly engaging the outermost convolution of the spring for preventing lateral displacement of the spring with respect to the member.

In testimony whereof I affix my signature.
